UNITED STATES PATENT OFFICE

126,079

DESIGN FOR A CASING FOR AN INTERNAL GRINDER OR SIMILAR ARTICLE

Richard C. Montanus, Springfield, Ohio, assignor
to The Springfield Machine Tool Co., Spring-
field, Ohio, a corporation of Ohio

Application November 9, 1940, Serial No. 96,451

Term of patent 14 years

To all whom it may concern:

Be it known that I, Richard C. Montanus, a citizen of the United States, residing at Springfield, in the county of Clark and State of Ohio, have invented a new, original, and ornamental Design for a Casing for an Internal Grinder or Similar Article, of which the following is a specification, reference being had to the accompanying drawings, forming part thereof.

Fig. 1 is a front perspective view of a casing for an internal grinder or similar article showing my new design;

Fig. 2 is a side elevational view taken from the left of Fig. 1;

Fig. 3 is a side elevational view taken from the right of Fig. 1; and

Fig. 4 is a rear elevational view thereof.

I claim:

The ornamental design for a casing for an internal grinder or similar article, as shown.

RICHARD C. MONTANUS.
